UNITED STATES PATENT OFFICE.

ERNEST G. SCHWARZ, OF NEW YORK, N. Y.

STATION-INDICATOR.

SPECIFICATION forming part of Letters Patent No. 723,739, dated March 24, 1903.

Application filed October 31, 1902. Serial No. 129,620. (No model.)

To all whom it may concern:

Be it known that I, ERNEST G. SCHWARZ, a citizen of the United States, residing at the city of New York, in the borough of Manhattan and State of New York, have invented certain new and useful Improvements in Station-Indicators, of which the following is a full, clear, and exact description.

This invention is an indicating device especially adapted for indicating stations or streets on railways, although it may be used for any purpose where it is desired to show at intervals various signs, characters, pictures, or information of any kind.

15 The invention involves a pair of rollers which carry a web upon which are the signs or pictures to be exhibited, a motor, and suitable clutch and tripping mechanism for moving the web step by step in a given direction 20 and for reversing the movement at any time desired.

The invention will be described in detail with reference to the accompanying drawings, in which—

25 Figure 1 is a plan or face view of the apparatus with parts broken away and parts in section. Fig. 2 is an end elevation of the device, showing the mechanism on both ends in dotted lines. Fig. 3 is a detail.

30 A indicates the framework, consisting, essentially, of three parallel plates connected together by binding-rods similar to ordinary clock-frames.

B and B' indicate two rollers adapted to 35 carry a web C, which leads from one roller to the other, passing over guide-rods b b and behind a glass set into an outer inclosing case, a part C' of which is shown. This web C will contain the names of the various streets or 40 stations in succession on a railway, or it may contain bits of information of any character intended to be shown in succession. The shaft b' of roller B is mounted to slide longitudinally in its bearings in the frame. One 45 end carries a pinion e and a disk e', having a shoulder e² upon its periphery. At the other end this shaft projects through the frame and is provided with an annular groove e³. Roller B' is similarly mounted in its bearings, its 50 shaft being provided on one end with a pinion f and disk f', having a shoulder f², and on

the other end, also projecting through the frame, an annular groove f³.

On one side of the apparatus is placed a spring-motor consisting of a spring-drum G 55 and two trains of gearing g and g', both driven thereby. The last wheel of the train g (indicated by g²) is in a position to be engaged by the pinion e, while the last wheel of the other train (indicated by g³) is in a position to be engaged by the pinion f. When one pinion is in engagement with its train, the other pinion is out of engagement with its train, and whichever train is operating determines the direction of movement of the web. 60 On that end of the apparatus opposite the motor is mounted a rock-shaft h, having an arm h', by means of which it can be rocked slightly. This shaft also carries a double-ended bar, one end i of which engages with 65 the annular groove in shaft b' by means of a forked end, while the other arm i' leads in the opposite direction and similarly engages with the annular groove in the shaft b². The free end of the arm h' has attached 70 to it two cords j and j', leading in opposite directions therefrom and over suitable guide-pulleys k and k' to points conveniently reached for manipulation. Adjacent to the 75 respective disks e' and f' are arranged two levers l and m, the former being pivoted at one extremity l' to the frame-plate and the latter being pivoted at an intermediate point m' to the frame-plate. The upper end of each lever carries a dog or detento, (shown in Fig. 3,) 80 adapted to engage with the shoulder of the disk opposite which it is placed. The lower end of lever m and an intermediate point of the lever l are connected together by a shifting-bar p, which is arranged inside of the 85 frame-plate, the connection with the two levers being by means of a pivot-pin passing through slightly-elongated openings in the frame-plate. A cord may be attached to the end of the shifting-bar so that it can be moved 90 longitudinally when desired, and a spring q, attached at one end to the frame-plate and bearing at the other end against the bar, returns the latter after it has been manually 95 moved.

The operation is as follows: By pulling on the cord j the shaft b' is thrown to the left

and the shaft b^2 to the right, causing pinion e to engage with its train and pinion f to become disengaged. The motor then rotates roller B in a direction to wind up the web and display a certain sign at the window in front of the apparatus. When the sign has become centrally placed, the shoulder e^2 on disk e' engages with the dog on the end of lever l and the rotation ceases. The sign remains in view 5 as long as desired, and when a change is necessary the shifting-bar p is pulled. This throws both dogs away from their respective disks, and the shaft being released, the motor again rotates roller B in the same direction 10 and is again stopped after one complete rotation by the engagement of the dog, the same having been released and carried back into position immediately after having been pulled. During these motions the shoulder on disk f' 15 does not engage with its dog because the rotation is not in the proper direction for engagement. When all of the signs have thus been successively shown, or in fact at any time during the passage of the web from one 20 roller to another, the direction of the step-by-step motion can be changed. This is done by pulling on the cord j' , which reverses the position of the arms i i' and throws pinion f into engagement with its train and pinion e out 25 of engagement. Then by operating the shifting-bar p , as before described, the web is moved step by step in the opposite direction. Hence one motor is used for movements in 30 both directions, and the apparatus is simple and easily controlled. Obviously other devices might be used to pull the various cords 35

or effect the various shifting movements, and my invention is not therefore limited to the particular means described.

It is needless to mention the various uses 40 to which a device of this kind can be applied, but I may state that I contemplate using it as a chart for purposes of instruction and as an advertising-machine for displaying pictures and other advertising matter. 45

Having described my invention, I claim—

1. In a movable sign apparatus, the combination of two rollers, a web adapted to be moved by the same, a motor, two trains of gearing driven thereby, devices adapted to 50 respectively connect the rollers with the trains of gearing, a detent for each roller and a single shifting device for both detents, substantially as described.

2. In a movable sign apparatus, the combination of two shafts movable longitudinally, a pinion and a notched disk carried by each shaft, two levers having dogs adapted to engage respectively with the notches in the disks, a shifting-bar acting simultaneously on 60 both levers, a motor, two trains of gearing driven by the motor and means for throwing one or the other of the pinions into engagement with a corresponding train, substantially as described. 65

In witness whereof I subscribe my signature in presence of two witnesses.

ERNEST G. SCHIWARZ.
